UNITED STATES PATENT OFFICE

2,545,468

APPARATUS FOR IMPREGNATING YARNS

Webster Jones, deceased, late of New York, N. Y., by Mildred Andrews Jones, administratrix, New York, N. Y., and John J. Heslin, Waltham, Mass., assignors to Chemo-Textiles, Inc., a corporation of Rhode Island

Application June 30, 1948, Serial No. 36,017

7 Claims. (Cl. 91—51)

1

This invention relates to apparatus for impregnating yarns. The word "yarns" is used herein to designate those materials specifically referred to in the trade as yarns and in addition materials of similar form and properties, such as cord, twine, string, and thread, whether of staple fibers or continuous filaments. In one method for the impregnation of yarns they are contacted with the impregnating agent in solution or suspension, followed by heating to dry and/or cure the impregnating agent, for example by polymerizing it, after which the yarn is wound upon a spool for transfer to point of ultimate use. Suitable impregnating agents, depending upon the purpose for which the yarn is to be used, are rubber latex, partially polymerized resins, preferably of the urea formaldehyde type in aqueous solution or suspension, cellulose derivatives in organic solvents, vinyl-butyl or vinyl chloride in aqueous dispersion, co-polymers of vinyl chloride and vinyl acetate in various ratios as solutions or dispersions, polyethylene in toluol or xylol, melamine formaldehyde and/or urea formaldehyde in aqueous dispersion.

The purposes for which the impregnation is applied include:

- (a) oil or water resistance
- (b) abrasion resistance
- (c) mildew and vermin resistance
- (d) increased strength
- (e) to set the twist thereby permitting the use of the yarns spun with less than the usual amount of twist
- (f) shrinkage control
- (g) reduction of fuzz
- (h) control of residual stretch
- (i) fire resistance

In all these cases the heating to dry and set or cure the impregnating agent must be done while the yarn is freely suspended, since the result would otherwise be to cement the yarn upon itself. Preferably the yarn is fed in individual spaced-apart form into contact with the impregnating agent, thence through the oven and thence to the winding spool. For economy of operation a number of yarns in spaced-apart form are usually fed through a common impregnating bath, thence through a common oven and thence to a winder containing a number of packages upon which the yarns are individually wound. This invention relates particularly to the apparatus for contacting the yarns with the impregnating liquid and will be fully understood

from the following description read in conjunction with the drawings in which:

Fig. 1 is a diagrammatic longitudinal section through the complete contacting, heating and winding apparatus;

Fig. 2 is a top view of part of the construction shown in Fig. 1;

Fig. 3 is a detailed vertical section through one part of the construction shown in Fig. 1;

Fig. 4 is a section through the construction shown in Fig. 3 on the plane indicated by 4—4, and

Fig. 5 is a diagrammatic cross-section through the construction shown in Fig. 1 on the plane indicated by 5—5.

Referring to Fig. 1, the yarn 1 to be impregnated enters the contacting apparatus 2, through guide 3, emerging after impregnation at 9 to enter the drying or curing oven 10, in which it is heated to temperature at which the solvent will be driven off and any desired change in the impregnating agent produced. After drying or curing it emerges from the oven at the point 100 to enter the winder 15 by which it is spooled.

Referring to Figs. 2, 3 and 4 for a detailed showing of the impregnating apparatus, tank 4 carries impregnating liquid 5, which is carried upwardly by roller 6, driven by shaft 7 projecting through the side wall of tank 4. Tank 4 is surrounded by a number of individual sections, such as 12 (Fig. 2). These are preferably formed of sheet metal and include vertically disposed side portion 13 and horizontally disposed top portion 14 (Fig. 4). Each section is mounted at point 15 for pivotal movement about shaft 16 which is carried (Fig. 2) by brackets 17 and 18, mounted on flange 19 secured to side wall 20 of tank 4.

Each individual section 12 may be independently tilted about the shaft 16 (Fig. 3) and the horizontal portions 14 collectively form a roof or cover over the tank (Fig. 2). Roller 21 (Fig. 3) is provided with the tire or rim 22 of resilient material, such as rubber, which rides upon and is driven by roller 6. Roller 21 is rotatably mounted on shaft 23 carried by bell arm 24. Bell arm 24 is pivotally secured to the side 13 of section 12 by rivet 25; the free end 26 of bell arm 24 is pivotally secured to the rod 27, which is in turn connected to spring 28, secured by rivets 29 to the horizontal top portion 14 of section 12. The tension applied by spring 28 is adjustable by means of the screw 20'. This provides an adjustable pressure between the rollers 6 and 21. Yarn 1 is fed into the bite 30 between these rollers 65 by guide roll 31 pivotally mounted by stud 32

in side wall 13 of section 12. After emerging from the bite the yarn passes through wire loop guide 34 into the bite 35 between squeeze rollers 36 and 37. Roller 36 is rotatably mounted by stud 38 in side wall 13 of section 12 while squeeze roller 37 is rotatably mounted by stud 39 in bracket 41 carried by spring 42. The tension of spring 42 and therefore the pressure between squeeze rollers 36 and 37 is manually adjustable by the two screws 43 and 44 threaded into horizontal top portion 14 of section 12. Upon emerging from bite 35 of rollers 36 and 37 the yarn passes through an additional squeeze provided by the two stationary cones 45 and 46 of resilient material. Cone 45 is secured to the side wall 13 by bracket 47 held in position by screw 48, while cone 46 is carried by bracket 51 pivotally mounted by stud 52 on side wall 13. The pressure between cones 45 and 46 is adjustable by tension spring 53.

As is evident from the foregoing, any one of the sections 12 may be tilted about the shaft 16, thereby breaking contact between the rollers 6 and 21. While these are in contact, they draw yarn 1 into the bite 30 between said rollers and thereby feed the yarn into the impregnating apparatus. The tilting of the section by breaking this contact automatically stops the feed of the individual yarn controlled by the particular section.

For the purpose of drying and/or curing, we preferably employ an oven 101 of the type shown and claimed in our copending application, Serial No. 36,018 filed June 30, 1948, which has sides 102 and 103 and a roof 104 but no bottom, and therefore defines an inverted open bottom trough 105 (Fig. 1 and 5). Means is provided for heating the interior of the trough and the yarn, in freely suspended form, is drawn through the oven by winder 151. The oven is preferably relatively long and may, for example, have a length of from 20 to 50 feet. One advantage inherent in this type of oven is that if a yarn breaks it immediately drops by gravity out of the zone of heat, thereby automatically preventing over-curing or burning, and visually apprising the operator of the particular yarn requiring his attention. As a number of yarns are preferably fed simultaneously through the same curing oven, it is preferred to provide a number of vertically oriented longitudinally extending fins 106 (Fig. 5) suspended from transverse rods 107 carried in side walls 102 and 103. Fins 106 are held in spaced relationship by spools 108 encircling rods 107. These fins divide the trough into a number of parallel open-bottom channels 109, through the center portion of which the yarn, in freely suspended form, is drawn by winding apparatus 151. While any suitable heating means may be employed, there is preferably used a number of transversely arranged electrical resistance heater elements 111, supported by side walls 102 and 103, located beneath roof 104 and immediately above the tops of the depending fins 106. These heater elements maintain a uniform and controllable temperature within oven 101. In practice the heater elements 111 are subdivided or grouped into a number of individual circuits, each including several resistor elements, so that the heat input of each individual group may be individually controlled, for example by a thermostat operating through an electrical relay switch. Suitable temperature measuring devices (not shown) are mounted at various points within the oven to apprise the operator of the exact

temperature obtaining within each part of the oven. As indicated in Fig. 5, each of the fins 106 is provided at its lower edge with the channel-shaped stiffener 112 to minimize warping or buckling.

Preferably each yarn as it emerges from the oven (or some other suitable point) passes in association with a stop motion device, such as that diagrammatically indicated by 152, including a vertical lever 153 carrying at its upper end the wire loop 154 which rests lightly on the yarn and through lever 155 controls microswitch 156. The construction is such that whenever the yarn breaks and lever 153 is no longer supported by the yarn, it will operate to close contact in microswitch 156, thereby causing electric current to travel through the leads 157 and 158 (Fig. 1).

Referring again to Fig. 3, the horizontal top portion 14 of section 12 is provided with upstanding stud 55 provided with the projecting shelf 56 secured between two lock nuts. The shelf 56 projects into the open jaw 57 of plate 58 pivotally carried by stud 61 attached to bracket 62, which in turn is riveted to the upright member 63. Plate 58 is normally urged in the direction indicated by arrow 64 by means of the tension spring 65 but is prevented from so doing by the latch 66 engaging end 67 of rod 68, which is also pivoted to plate 58 at the point 69. The latch 66 is pivotally secured at the point 71 to the upright 63 and is also pivotally secured at 72 to the plunger 73 of solenoid 74. Whenever the stop motion device 152 becomes operative and current flows through the leads 157 and 158, the solenoid 74 is energized, thereby lifting the latch 66 and permitting the plate 58 to move upwardly in the direction indicated by arrow 64. The same movement releases lever 75 thereby opening microswitch 76 and interrupting the flow of current through solenoid 74 until normal operation is reestablished.

Whenever the stop motion device 152 is actuated by the breaking of a yarn, the particular impregnating section feeding said yarn will automatically and immediately be tilted upwardly about the pivot point 15 thereby instantly apprising the operator of the particular impregnating section requiring his attention. Inasmuch as section 12 is open at one side, the operator may, merely by manually tilting the section, still further expose the guide and roller mechanism and, if necessary, rethread the yarn within the impregnating device in the matter of a few seconds.

The foregoing description is for purposes of illustration and not of limitation and it is therefore our intention that the invention be limited only by the appended claims or their equivalents wherein it has been endeavored to claim broadly all inherent novelty.

60 We claim:

1. In apparatus of the tank type for simultaneously contacting a number of yarns with impregnating liquid, the improvement in combination with the tank of such apparatus of a roof covering said tank, said roof being composed of a number of sections in parallel, each section being formed with a horizontally disposed top portion, each section carrying means for guiding individual yarn into contact with said liquid and each section being pivotally mounted to render accessible the guiding means carried thereby, and means cooperatively associated with each said sections for selectively pivoting any section affected by breakage of yarn delivered by such section.

2. In apparatus of the tank type for simultaneously contacting a number of yarns with impregnating liquid, the improvement in combination with the tank of such apparatus of a number of sections in parallel surmounting said tank, each section being formed with a vertically disposed side portion, each side portion carrying means for guiding an individual yarn into contact with said liquid and all sections being pivotally mounted about a common axis to permit tilting of any selected section to render accessible the guiding means carried thereby, and means cooperatively associated with each said sections for selectively pivoting any section affected by breakage of yarn delivered by such section.

3. In apparatus of the tank type for simultaneously contacting a number of yarns with impregnating liquid, the improvement in combination with the tank of such apparatus of a roof covering said tank, said roof being composed of a number of sections in parallel, each section being formed with a vertically disposed side portion and a horizontally disposed top portion, each said side portion carrying means for guiding an individual yarn into contact with said liquid and each section being pivotally mounted to render accessible the guiding means carried thereby, and means cooperatively associated with each said sections for selectively pivoting any section affected by breakage of yarn delivered by such section.

4. In apparatus of the tank type for simultaneously contacting a number of yarns with impregnating liquid, the improvement in combination with the tank of such apparatus of a number of sections in parallel, each section carrying means for contacting an individual yarn with said liquid, all of said sections being mounted for pivotal movement about a common axis, a stop motion device cooperatively associated with a yarn delivered by each said section for actuation upon breakage of said yarn, and means for mechanically tilting each said section controlled by the associated stop motion device.

5. In apparatus of the tank type for simultaneously contacting a number of yarns with impregnating liquid, the improvement in combination with the tank of such apparatus of a number of sections in parallel, each section carrying means for contacting an individual yarn with said liquid, all of said sections being mounted for pivotal movement about a common axis, a drive roll mounted in said tank parallel to said axis, a driven roll carried by each said section adapted to contact with and be driven by said drive roll, and means for guiding a yarn into the bite between said drive and driven rolls whereby the yarn is fed into the impregnating apparatus, the feed into any particular section controlled by said bite being automatically discontinued on tilting said section, and a stop motion device cooperatively associated with a yarn delivered by each said section for actuating upon breakage of said yarn, and means for mechanically tilting each said section controlled by the associated stop motion device.

6. In apparatus of the tank type for simul-

taneously contacting a number of yarns with impregnating liquid, the improvement in combination with the tank of such apparatus of a number of sections in parallel, each said section being formed with a vertically disposed side portion, each said section carrying means for guiding an individual yarn into contact with said liquid, all of said sections being mounted for pivotal movement about a common axis, a drive roll mounted in said tank parallel to said axis, a driven roll mounted on each said side portion adapted to contact with and be driven by said drive roll, and means guiding a yarn into the bite between said drive and driven rolls whereby the yarn is fed into the impregnating apparatus, the feed into any particular section controlled by said bite being automatically discontinued on tilting said section, and a stop motion device cooperatively associated with a yarn delivered by each said section for actuation upon breakage of said yarn, and means for mechanically tilting each said section controlled by the associated stop motion device.

7. In apparatus of the tank type for simultaneously contacting a number of yarns with impregnating liquid, the improvement in combination with the tank of such apparatus of a number of sections in parallel, each section being formed with a vertically disposed side portion and a horizontally disposed top portion, said top portions collectively forming a roof over said tank, each said section being mounted for pivotal movement about a common axis, a drive roll mounted in said tank parallel to said axis, a driven roll mounted on each said vertically disposed side portion adapted to contact with and be driven by said drive roll, and means guiding a yarn into the bite between said drive and driven rolls whereby the yarn is fed into the impregnating apparatus, the feed into any particular section controlled by said bite being automatically discontinued on tilting said section, and a stop motion device cooperatively associated with a yarn delivered by each said section for actuation upon breakage of said yarn, and means for mechanically tilting each said section controlled by the associated stop motion device.
